DESIGN FOR A SINK STOPPER

Catherine Petterson, Brooklyn, N. Y.

Application July 18, 1935, Serial No. 57,722

Term of patent 3½ years

To all whom it may concern:

Be it known that I, Catherine Petterson, a citizen of the United States, residing at Brooklyn, New York, in the county of Kings and State of New York, have invented a new, original, and ornamental Design for Sink Stoppers, of which the following is a specification, reference being had to the accompanying drawing, forming part thereof.

Fig. 1 is a perspective view of a sink stopper showing my new design.

Fig. 2 is a side elevational view of the same.
Fig. 3 is a bottom view of the same.

I claim:

The ornamental design for a sink stopper as shown.

In testimony whereof I have affixed my signature.

CATHERINE PETTERSON.
